UNITED STATES PATENT OFFICE

2,256,110

REFRIGERATED CONTAINER

Leonard F. Clerc, Chicago, Ill.

Application March 9, 1939, Serial No. 260,703

7 Claims. (Cl. 62—91.5)

My invention relates generally to refrigerated containers, and more particularly to improvements in compact shipping containers for use in the shipment of frozen foods and other foods or products which it is desired to maintain at a relatively low temperature.

It is an object of my invention to provide an improved refrigerated shipping container which is compact, may be easily handled, and has provisions for refrigerating its contents by means of dry ice, or other refrigerant.

A further object is to provide a refrigerated shipping container which may conveniently be used as a cabinet by the consignee, and may thus be used to maintain its contents at a low temperature until they are sold. Thus, a retail grocery store may utilize the container as a temporary refrigerator for the storage of the food products until they are sold, and then upon the delivery of a filled container, return the empty one, in this manner facilitating the shipment and storage of the food, and the return of the empty containers.

A further object is to provide an improved refrigerated container in which adequate circulation of air in the container is readily maintained, thereby to insure that even if the container is packed full of packaged food products, the contents will be maintained at the requisite low temperature.

A further object is to provide a refrigerated container which may conveniently be used with ice or dry ice as the refrigerating medium, or which may be connected to a mechanical refrigerating unit.

A further object is to provide an improved refrigerated cabinet which may conveniently be connected to the evaporator circuit of a mechanical refrigerating unit, enabling the container to be used as a subscriber's locker in a cold storage plant.

Other objects will appear from the following description, reference being had to the accompanying drawings, in which:

Figure 1 is a front elevational view of the container, with the doors thereof in closed position;

Figure 2 is a front elevational view of the container, with the doors in open position;

Figure 3 is a vertical sectional view of the container, taken on the line 3—3 of Figure 4;

Figure 4 is a vertical sectional view taken on the line 4—4 of Figure 3;

Figure 5 is an enlarged fragmentary sectional view of the top portion of the container, showing particularly the dry ice compartment;

Figure 6 is an enlarged fragmentary sectional view taken in a plane perpendicular to that of Figure 5;

Figure 7 is a horizontal sectional view taken on the line 7—7 of Figure 6;

Figure 8 is a fragmentary vertical sectional view of a modified form of the invention, in which the container is connected to a mechanical refrigerating system;

Figure 9 is a fragmentary sectional view of a second modified form of the invention; and,

Figure 10 is a fragmentary vertical sectional view of a third modified form of the invention.

In the past, considerable difficulty has been experienced in the transportation of refrigerated and frozen foods, due to the difficulty of maintaining the food products at the necessary low temperature throughout transit from the packer to the retail establishment selling the products.

For the supply of such food products to larger cities, the problem has been solved in a measure by shipping the food products in refrigerated freight cars and unloading them directly into a cold storage warehousing plant. In some instances, refrigerated trucks have been utilized to transport the food products from the cold storage warehouses to the retail stores. In the smaller cities, however, the consumption of frozen and refrigerated foods is insufficient to warrant shipment of the food in carload lots, and proper cold storage facilities are usually not available. As the result, the distribution of refrigerated foods, and particularly quick frozen food products, has been largely limited to the larger cities.

By making use of the refrigerated container of my invention, refrigerated and frozen foods may be shipped in the manner of other food products, since the container is thoroughly insulated, and is provided with a self-contained refrigerating means, whereby the food in the container may be maintained at the requisite low temperature throughout transit from the packer to the retailer. The containers are of a size approximating that of a large trunk, so that they may be conveniently handled by a single man in loading them in the freight cars, and unloading them from the freight cars on to trucks. They are made sufficiently light in weight so as not to add excessive tare to the weight of the shipment, are made very durable so as to withstand the rough handling to which they are subjected, and are so simple in construction, and employ such a simple method of refrigeration that they may be serviced by relatively unskilled help.

Exemplary forms of my invention are shown

in the drawings, the forms shown in Figs. 1 to 7, inclusive, comprising a metal shell forming an outer box 20, the walls 22 of which are preferably corrugated to increase their rigidity, the walls being joined at their edges by rigid angles 24, preferably by welding. The front panel 26 is provided with openings which are closed by hinged doors 28 and 30, the door 28 providing access to the food product compartment 32, while the door 30 provides access to the refrigerating compartment 34. The compartments 32 and 34 are formed by welded corrugated sheets 36, the corrugations in the vertical walls thereof extending vertically to provide a space for the circulation of air about the contents of the container.

As best shown in Figs. 5 and 6, a tank-like housing 38 is supported on projections 39 which may be stamped from, or welded to, the side walls 36, and is further held in position by abutment of lugs 41 which may be welded to the top of the housing 38 and abut the top wall of the inner case. The housing 38 is formed of pressed metal corrugated sheets which are welded together. The open end of the housing 38 has a frame 40 welded thereto, the frame being drilled and tapped at suitable intervals to receive cap screws 42, which a cover 44 is secured over the open end of the housing 38. A gasket 46, preferably of buckskin, is utilized to seal the joint between the cover 44 and the frame 40. The cover 44 may be hinged to a bracket 48 formed integrally with or welded to the frame 40, and is tapped to receive a pressure gauge 50 and a manually operable pressure relief valve 52. The housing 38 is adapted to be filled with dry ice or similar refrigerant, the carbon dioxide evaporating therefrom being conducted through suitable pipe connections 54 to a pressure regulating valve 56 from which the carbon dioxide flows through a serpentine coil 58 through a manually operated pressure control valve 60 and a vent duct 62 to the atmosphere. The coil 58 is secured by clips or the like to a plate 64, which, in turn, is secured by Z-shaped bars 66 with the housing 38. The spaces between the Z-shaped bars 66 form passageways for the circulation of air between the bottom of the housing 38 and the plate 64. These passageways are open at their ends, and thus provide paths for the circulation of air, and thereby facilitate maintaining the contents of the container at a low temperature. It will be noted that the housing 38 is spaced slightly from the walls 36 of the chamber 34, so that its entire exterior surface may be contacted by the air within the container.

The pressure regulating valve 56 is preferably of the adjustable spring loaded type, and may be set to permit venting of the carbon dioxide in the housing 38 to the atmosphere whenever the pressure in the housing exceeds a predetermined value, such as ten or fifteen pounds per square inch. By maintaining the carbon dioxide in the housing 38 under pressure, the rate of evaporation may be reduced thereby to maintain the food products in the container at the desired low pressure without the inefficiency inherent when the dry ice is permitted to evaporate freely and thus lower the temperature of the contents of the container below a value necessary to maintain the products in good condition.

The connection between the vent pipe 62 and the valve 60 is an ordinary threaded connection, so that the vent pipe may be unscrewed from the

valve 60, whereupon the assembly, consisting of the casing 38 and all parts secured thereto, may be removed from the container as a unit. Convenient means may be provided to lock the casing rigidly in position, as determined by the brackets 39 and lugs 41. Thus, if it should become necessary to repair or replace the dry ice receiving casing 38, it may be removed for such repair, and a similar unit substituted therefor, making it unnecessary to keep the entire container out of service during the time consumed in making such repairs.

The top of the container is provided with a handle 70 which is welded or otherwise suitably secured to the top of the container, so that the container may be easily tipped so as to rest upon a pair of rollers 72, which are secured to the side of the container adjacent the bottom thereof, by suitable bearing brackets 74 which may be welded or riveted to the angle iron 24 which extends along the side bottom edge of the container.

The door 30 is provided with a suitable shipping tag holder 76, which may be of any suitable form to receive the shipping labels or tags.

The doors 28 and 30 are provided with suitable locking means to hold them securely in closed position, such locking means being illustrated as simple latches 78, these locking means being preferably of a type which has means for receiving seals 80.

The flanges of the doors are provided with rubber gaskets 82, so as to make the container substantially air tight.

The door jambs are lined with strips 84 of heat insulating material, such as Bakelite. The inner case formed by the ribbed or corrugated sheets 36 is spaced from the outer housing 40 formed by the sheets and panels 26 by suitable struts or spacers 86, and the space between the inner case and outer housing is filled with suitable heat insulating material 88. The doors 28 and 30 are likewise filled with a heat insulating material. The material is packed in tightly so as to form a cushioning backing for the sheets 26 forming the outer walls of the container.

In using the container, the products to be shipped, having preferably been pre-cooled, are placed in the compartment 32 and may be packed in to this compartment tightly, because adequate circulation of cooling air about the products is assured by virtue of the spaces between the ribs or corrugations formed on the inside walls 36 of the compartment. Depending upon the expected time that the container will be in transit, the casing 38 may be filled or partially filled with dry ice. The casing 38 is then sealed by securely clamping the cover door 44 over the end opening thereof. Upon opening the valve 60, the doors 28 and 30 may be closed and sealed, whereupon the container will be in condition for shipment. During transit, the dry ice will, of course, evaporate at a rate determined in part by the setting of the pressure relief valve 56, and due to the circulation of air in the container around the casing 38, as well as through the passageways formed between the Z-shaped bars 66, the food or other product within the container will be maintained at any predetermined low temperature. The carbon dioxide gas evaporating from the dry ice is, of course, caused to flow through the coil 58, and during the course of such flow expands, thus increasing its refriger-

erating properties so that a maximum amount of heat will be carried from the container.

Upon receipt of the container, the consignee, upon opening the door 38, may note the reading of the gauge 50, and if pressure is still maintained in the casing 38, he is assured that the shipment has been maintained at the required low temperature throughout transit. He may therefore use the container as a temporary refrigerator, and remove the contents as they are sold, replenishing the dry ice in the casing 38 only when the need is indicated by the drop in the pressure within the casing 38, as shown by the gauge 50. If it is not necessary to keep the contents at a very low temperature, the consignee may place ice in the casing 38, being, however, careful to drain the casing after the ice has melted. Whenever it is necessary to open the cover door 44 while the pressure within the casing 38 is still above atmospheric pressure, it is desirable to vent the casing by opening the valve 52 prior to unscrewing the cap screws 42, and thus prevent possible damage to the sealing gasket 46.

In Fig. 8, I have shown a modified form of my invention wherein the container is adapted to be connected to an external source of a refrigerating medium. This type of installation may conveniently be used in food storage locker plants.

The container proper may be of the same construction as shown in Figs. 1 to 7, inclusive, with the exception of the refrigerating unit installed therein. In Fig. 8, the refrigerating unit comprises a tank 100, which is generally rectangular in both vertical and horizontal cross section, and has a plurality of depending ribs 102 formed in the bottom surface thereof to provide passageways 104 for the circulation of air. The tank is preferably filled with a suitable liquid having a low freezing point, such as alcohol or brine, the tank being filled through a filling pipe 106 normally closed by a plug 108. The tank 100 may be drained through a similar drain pipe 110, which is normally closed by a pipe plug 112. Within the tank 100 is a compartment 114, one end of which is open and extends through an opening formed in the front end of the tank 100, the opening being normally closed by a suitable door. The compartment 114 is available for freezing food products, and is surrounded by a coil 116, the ends of which are connected to conduits 118 and 120. These conduits supply to and carry away from the coil 116 a suitable refrigerating medium. The coil 116 may thus be a portion of the evaporator coil system of a mechanical refrigerating unit, and in this event a suitable expansion valve will be provided to control the flow of the refrigerating medium into the coil 116. In other installations where a brine circulating system is used, the conduit 118 may be connected to the pressure side of the brine circulating system, while the conduit 120 forms the return.

With containers shown in Fig. 8, a locker storage plant may be constructed in which the subscribers, or owners of the plant, may have access to the stored food owned by them without having to go into a chilled or cooled room. Furthermore, the food within the container is substantially sealed, so that it is unnecessary to take the usual precautions to prevent excess evaporation of moisture from the food.

The modified form of my invention shown in Fig. 9 is likewise adapted for use in locker stor-

age plants or other places where the container may be connected to a suitable supply of a refrigerating medium. In this construction, the container is provided with a coil 122 which surrounds a casing 124 divided into passageways by plates 126 and 128. The conduit forming the coil 122 extends along the side walls of the internal compartment of the container, as indicated at 130, so that the food compartment of the container is chilled throughout its length. The coil 122 and the extended conduit 130 thereof may constitute an expansion coil of a refrigerating apparatus, or may have brine or other cold fluid or liquid circulated therethrough.

In the modification shown in Fig. 10, there is provided a casing 132 which has welded thereto at the bottom a tank 134 containing alcohol or other liquid having a low freezing point. In this construction, the casing 132 is adapted to be filled or partially filled with dry ice, while the tank 134 and the alcohol or other liquid contained therein forms a heat conducting means, as well as a heat reservoir. The tank 134 may be filled and drained through pipes 136 and 138, respectively, which are normally closed by suitable pipe plugs or caps. The type of dry ice containing casing shown in Fig. 10 may, if desired, be utilized in conjunction with the refrigerated container shown in Figs. 1 to 7, inclusive.

The operation of the modified forms of my invention shown in Figs. 8, 9 and 10, will, of course, be similar to that of the preferred form shown in Figs. 1 to 7, inclusive, except that it will be understood that the forms of the invention shown in Figs. 8 and 9 are adapted primarily as individual insulated locker devices in locker storage plants, rather than as shipping containers.

By having a locker storage plant provided with an individual food storage cabinet of the type shown and described, each subscriber may rent one or more of the cabinets as his particular locker or lockers, and only those cabinets which have food or other products stored therein by the subscribers need be connected to the central refrigerating unit of the plant. An economy in the size of the central refrigerating unit and in its power operating costs may thereby be effected. Furthermore, the building housing the locker storage plant need not be heat insulated, and this may be of a more economical construction. Due to the fact that the containers may, if desired, be located in a room kept at a moderate temperature, the subscribers may have access to their containers without the discomfort and danger to health entailed by entering a room maintained at a very low temperature.

The modification of the invention shown in Fig. 10 may, of course, be used as a shipping container, as well as a refrigerator for more general uses.

It will be noted that in all of the constructions in which dry ice is used as the refrigerating medium, the resulting carbon dioxide is not permitted to come in contact with the contents of the container, but instead is conducted directly to the atmosphere. This is of considerable advantage when the container is used to transport certain foods which are injuriously affected by being maintained in an atmosphere of carbon dioxide for an appreciable length of time.

While I have shown and described particular embodiments of my invention, it will be apparent to those skilled in the art that numerous variations and modifications thereof may be made without departing from the underlying prin-

ples of my invention. I therefore desire, by the following claims, to include within the scope of my invention all such similar containers whereby substantially the results of my invention are obtained by substantially the same means I claim.

I claim:

1. In a refrigerated container for the shipment of frozen foods and the like, the combination of a cabinet having heat insulating walls and two doors opening thereinto, an air-tight casing secured within said cabinet and having means for charging it with dry ice, means for maintaining the pressure within said casing at a super-atmospheric pressure to decrease the rate of evaporation of dry ice contained in said casing, a plurality of air circulating passageways having walls in heat conducting relationship with said casing, said passageways being accessible for cleaning and defrosting upon the opening of one of said doors.

2. The combination set forth in claim 1, in which said passageways are formed directly beneath said casing, and have open ends for the circulation therethrough of air in said container.

3. In a portable refrigerated container for the shipment and storage of frozen foods and the like, the combination of a cabinet having heat insulated walls having vertically extended corrugations along the interior surface thereof to assure circulation of air in said cabinet around products closely packed therein, a pair of doors opening thereinto, an air-tight casing secured within said cabinet and located at the top thereof, means for charging said casing with dry ice, a conduit connecting the interior of said casing with the atmosphere, and a pressure controlling valve in said conduit operable to control the rate of evaporation of dry ice in said casing by maintaining the contents of said casing at a predetermined superatmospheric pressure.

4. In a portable refrigerated container for the shipment and storage of frozen foods and the like, the combination of a cabinet having heat insulated walls having projections on the interior thereof to assure a space for circulation of air between the cabinet walls and closely packed packages contained within the cabinet, and a pair of doors opening into said cabinet, an airtight casing secured within said cabinet and located at the top thereof, means for charging said cas-

ing with dry ice, a conduit connecting the interior of said casing with the atmosphere, and a pressure controlling valve in said conduit operable to control the rate of evaporation of dry ice in said casing by maintaining the contents of said casing at a predetermined superatmospheric pressure.

5. In a portable refrigerated container for the shipment and storage of frozen foods and the like, the combination of a cabinet having heat insulated walls and a pair of doors opening thereinto, an airtight casing secured within said cabinet and having means for charging it with dry ice, a conduit in the form of a circuitous pipe located a spaced distance beneath said casing and connecting the interior of said casing with the atmosphere, a pressure controlling valve in said conduit operable to control the rate of evaporation of dry ice in said casing by maintaining the contents of said casing at a predetermined superatmospheric pressure, and passageways for the circulation of air formed in a space between said pipe and said casing.

6. In combination, a cabinet having heat insulating outer walls and having doors for obtaining access to the interior of the cabinet, a casing having a dividing wall separating said casing into an upper and lower compartment, means for cooling the interior of said upper compartment, a liquid having a freezing point lower than that of water contained in said lower compartment, and means providing passageways along the vertical interior walls of said cabinet to permit the circulation of air around closely packed contents of said container toward and away from said casing.

7. In combination, a cabinet having heat insulating outer walls and having doors for obtaining access to the interior of said cabinet, a casing secured adjacent to the top within said cabinet, a coil surrounding said casing, a conduit connected to said coil extending adjacent the interior wall of said cabinet, means for circulating the refrigerating means through said coil and conduit, and means providing passageways along the vertical interior walls of said cabinet to permit the circulation of air around closely packed contents of said cabinet toward and away from said casing.

LEONARD F. CLERC.
